UNITED STATES PATENT OFFICE.

JOHN S. DONALDSON, OF NEW YORK, N. Y.

TOOL AND TOOL RETAINER.

Application filed May 1, 1920. Serial No. 378,339.

To all whom it may concern:

Be it known that I, JOHN S. DONALDSON, a citizen of the United States, residing at New York city, in the county of Queens and 5 State of New York, have invented certain new and useful Improvements in Tools and Tool Retainers, fully described and represented in the following specification and the accompanying drawings, forming a part of 10 the same.

This invention relates to improvements in tools and tool retainers and has for an object to provide a tool retainer in which a tool is securely held and from which it may 15 easily be withdrawn when desired.

In accordance with the invention the tool retainer is provided with two tool engaging means. One of these engaging means is so mounted in the tool retainer that 20 it cannot be rotated with respect to the tool retainer, and is adapted to hold the tool in the retainer but to permit the tool to be withdrawn from the retainer when turned in one direction. The other engaging means 25 fits upon the tool in such a way as to prevent the turning of the tool with respect to it. This engaging means is rotatably mounted in the retainer, but provided with releasable locking means to prevent its rotation with 30 respect to the retainer.

The invention possesses peculiar advantages when used in connection with pneumatic chisels. By this term I include any device in which a tool is given a vibratory 35 motion by means of compressed gas, whether the device is provided with a tool in a conventional chisel form or with any other form of cutting tool, or with a hammering tool for heading rivets or other purposes. 40

The pneumatic chisels which have been commonly used for stone cutting and other purposes consist of a handle containing a hammer which is reciprocated by compressed air or other gas supplied to the handle. The outer end of the handle is customarily provided with a round central hole through which the round end of the shank of the tool is inserted. In using this 45 device the workman grasps the handle with one hand and with the other holds the shank of the tool. He must hold the shank firmly in order properly to direct the cutting edge of the tool and to prevent the tool from 50 turning in the round hole in which the up-

per end of its shank is inserted. He must also continuously pull the tool into the handle so as to bring its upper end in contact with the reciprocating hammer. He is thus required continuously to take a firm grip upon the 60 tool which is oscillating under the blows of the hammer. Using the device in this manner causes a constant vibration of one hand and arm of the workmen which has been found to result in serious injury to the work- 65 man, being frequently the cause of palsy.

My tool retainer when applied to a pneumatic chisel comprises a casing attached to the handle to guide the tool, and resilient means to throw the tool inwardly against 70 the hammer in order that it may be constantly subjected to the hammer blows. The workman guides the tool by placing one hand upon the handle as before and the other upon the fixed tool-guide attached to 75 the handle. Both his hands are thus upon comparatively stationary parts of the device. Furthermore, the grip required is just sufficient to guide the tool, not the firm grip formerly necessary to pull the tool back 80 against the hammer. The workman's hands and arms, therefore, are not subject to undue vibration. The tool may in consequence be used for long periods without any resultant 85 injury to the workman.

In order that my invention may clearly be understood, I will describe in detail the embodiment of it shown in the accompanying drawings, in which

Fig. 1 is a side view of a complete pneumatic chisel provided with my improvement, showing the cover plate removed; 90

Fig. 2 is a central longitudinal section of the portion of the device incorporating my improvements; 95

Fig. 3 is a transverse section taken on the line 3—3 of Fig. 2 in the direction of the arrows;

Fig. 4 is a transverse section taken on the line 4—4 of Fig. 2 in the direction of the 100 arrows;

Fig. 5 is a side view of a tool used in my device.

I make use of the handle 10 customarily used in pneumatic chisels and containing a 105 pneumatically operated hammer, the outer end 11 of which is shown in Fig. 2. The outer end 12 of the handle 10 is provided with the customary central opening to admit the round end of the shank of the tool, and 110

as is usual, in this opening is fixed a sleeve 13 provided with a collar portion 13^a to limit the inward movement of the tool. The external surface of the outer end 12 of the handle 10 is made cylindrical and part or all of it is provided with external screw threads 14.

The tool retainer, comprising the sleeve 15 and the parts next described, is attached 10 to the handle 10 by screwing the sleeve 15 upon the screw threads 14. A set screw 46 prevents the sleeve 15 from unscrewing from the handle under the vibration caused by the hammer blows. It should be understood, however, that the particular means 15 illustrated for securing the sleeve 15 to the handle 10 are not essential to the invention as the sleeve may be attached to the hammer in any desired manner.

20 A rotatably mounted tool engaging means is located at or near the outer end of the sleeve 15 and may consist of a cap 16 which in the form illustrated is adapted to be screwed into the sleeve 15 and which has a central opening 17 of a shape to fit the outer portion of the shank of the tool. In the drawings, this portion of the shank and the opening are shown hexagonal in form (Fig. 4), as this is a form in which the tool shanks 25 are commonly made. The outer portion of the shank and the opening 17 may, however, be made square, or of any other shape, except circular.

The retainer is provided with non-rotary 35 engaging means to hold the tool in the retainer in position to be subjugated to blows of the hammer, which, in the form illustrated, comprises a plunger 20 within the sleeve 15 and consisting of an elongated 40 bearing sleeve 21 and a disc-shaped portion 22. The portion 22 is provided with an elongated aperture 23. A screw 24 is screwed into the plunger 20 and has a square head which projects into a groove 25 in the 45 sleeve 15 and thus prevents the plunger 20 from turning within the sleeve. The groove 25 may be cut clear through the sleeve 15 so as to form a slot as shown in the drawing, but this is not essential. At the upper 50 end of the groove 25 is provided with a circular hole 26 of diameter sufficient to permit the screw 24 to be screwed into the plunger 20 through it after the plunger has been inserted in the sleeve 15 and before the 55 sleeve 15 is screwed on the outer end 12 of the handle 10. After the sleeve 15 is screwed on, the outer end 10 of the handle prevents the plunger 20 from moving inwardly far enough to bring the head of the 60 screw 24 into the hole 26. The screw 24 is thus prevented from unscrewing under the vibration of the tool by the engagement of its square head with the walls of the groove 25. The groove 25, if cut through the sleeve 65 15 as shown, may be provided with a cover

plate 27 attached to the sleeve 15 by screws 28. Between the cap 16 and the plunger 20 is a compression spring 30 which is held in place by having its lower end bent and inserted in a groove 31 and hole 32 in the 70 cap 16.

In the cap 16 is a spring catch consisting of a plunger 33 urged inward by a compression spring 34 and provided with a stem 35 on which is screwed a button 36 to permit 75 the drawing of the plunger outwardly. The outer edge of the sleeve 15 is provided with a hole 37 having its bottom inclined upwardly in one direction, so that the plunger 33 catches in the hole 37 when the cap 16 is screwed outwardly from the sleeve 15, but slides out of the hole 37 when the cap 16 is screwed inwardly. In the lower edge of the sleeve 15 there is another hole 38 similar to the hole 37 and spaced at 90° from that 80 hole.

The tool 40 has a cutting or hammering portion 41, and a shank. The portion 41, shown as chisel shaped, may be made toothed, or pointed, or of any other shape 90 used for cutting stone or metal, or it may be made cup-shaped for heading rivets, or in any other desired form. The outer portion 42 of the shank is non-circular in cross-section (being shown as hexagonal). The 95 inner portion 43 of the shank is cylindrical. On the cylindrical portion 43 are two shoulders 44. The extreme width across the shoulders 44 is not greater than the width of the lower portion 42. Each of the shoulders 44 is provided at one of its outer edges with an inclined cam surface 45.

When the parts of the device are in the position shown in Fig. 2, the outer surface of the shoulders 44 are engaged by the inner surface of the disc portion 22 of the plunger 20 so that the tool is urged inwardly by the pressure of the spring 30 against the plunger 20. The spring 30 is of just sufficient strength to return the tool to the position shown in Fig. 2 in which the upper end of its shaft abuts against the collar 13^a after each outward blow of the hammer, but the spring is not strong enough to materially retard the tool when driven outwardly by a 110 blow of the hammer.

In using the device the workman places one hand upon the handle 10 and the other upon the sleeve 15. He is thus enabled to guide the tool without grasping an oscillating part of the device. Owing to the fit of the non-circular portion of the shank in the aperture 23, the workman may determine the angular position of the cutting edge of the tool by simply turning the handle and sleeve. The spring 30 serves to draw the tool inwardly after each hammer blow, so that the upper end of the shank is in position to be struck by the next outward blow of the hammer. The workman is, therefore, 120 125 130

not required to take any grip upon the oscillating tool.

When it is desired to remove the tool from the device for the purpose of substituting a new tool, or for any other purpose, it is merely necessary to pull out the button 36 so as to release the plunger 33 from the hole 37 and unscrew the cap 16 from the sleeve 15 a quarter of a turn until the plunger 33 enters into the hole 38. As the cap 16 turns with the tool 40, the cap 16 may be unscrewed by grasping the handle 10 or the sleeve 15 in one hand and the tool 40 with the other hand. When the cap 16 has been turned 90° so that the plunger 30 is seated in the hole 38, the shoulders 44 of the tool 40 are in line with the elongated aperture 23 in the plunger 20 so that the tool may be withdrawn.

If the new tool to be inserted is provided with a shank having its lower portion square in cross-section, or of other shape differing from that of the tool 40, the button 36 is again pulled out, and the cap 16 screwed out and a similar cap having a square or other aperture fitting the shank of the new tool is substituted. If, however, the new tool has the lower portion of its shank hexagonal like the tool 40, it may be directly inserted while the cap 16 is in such a position that the plunger 33 engages the hole 38. The shoulders 44 of the new tool will then register with and pass through the elongated opening 23 of the plunger 20. It should be noted that when there is no tool in the device the spring 30 will force the plunger 20 against the outer end 12 of the handle 10. After the tool has been inserted, the tool and the cap 16 are turned through an arc of 90° until the plunger 33 catches in the hole 37. In this movement of the tool the cam surfaces 45 of the shoulders 44 engage the inner surface of the disc portion 22 of the plunger 20 at the sides of the opening 23 and force the plunger 20 out away from the outer end 12 of the handle 10. The pressure of the spring 30 is thus applied through the disc portion 22 of the plunger 20 to the shoulders 44 of the tool and serves to urge the tool upwardly in position to be struck by the blows of the hammer 11.

Many modifications may be made in the device described without departing from my invention. It is apparent that the means used for giving the reciprocating motion to the hammer 11 do not form a part of my invention, and that the invention may be applied to devices in which the movement of the hammer is caused by other than pneumatic means. While the form of the casing and associated parts of the tool guide shown in the drawings is that which I have found most satisfactory, it will be apparent to skilled mechanics that many of the me-

chanical details described may be modified without materially affecting the operation of the device.

What is claimed is:

1. In combination with a handle containing a reciprocating hammer, a tool having a shank, the outer portion of which is non-circular in cross-section and the inner portion of which is of less diameter than the outer portion, a shoulder projecting from one side of the inner portion of the shank, a sleeve surrounding the shank of the tool and attached to the handle, a plunger in said sleeve having an aperture through which said shoulder may pass when turned in one position, means for preventing the rotation of said plunger relatively to said sleeve, and a cap rotatably mounted on said sleeve and containing an aperture fitting the non-circular portion of the shank of the tool, whereby turning of the tool and cap relatively to the sleeve brings said shoulder upon the tool shank into and out of alignment with the aperture in said plunger. 70 80 85

2. In combination with a handle containing a reciprocating hammer, a tool having a shank, the outer portion of which is non-circular in cross-section and the inner portion of which is of less diameter than said outer portion, a shoulder upon the inner portion of the shank, a sleeve surrounding the shank of the tool and attached to the handle, a plunger in said sleeve having an aperture through which said shoulder may pass when turned in one position, means for preventing the rotation of said plunger relatively to said sleeve, a cap rotatably mounted on said sleeve and containing an aperture fitting the non-circular portion of the shank of the tool, whereby rotation of the tool and cap relatively to the sleeve brings said shoulder upon the tool shank into and out of alignment with the aperture in said plunger, and releasable means arranged to lock the cap to the sleeve when said shoulder is in a position in which it is not in alignment with said aperture. 95 100 105 110

3. In combination with a handle containing a reciprocating hammer, a tool having a shank, the outer portion of which is non-circular in cross-section and the inner portion of which is of less diameter than the outer portion, a shoulder projecting from one side of the inner portion of the shank, a sleeve surrounding the shank of the tool and attached to the handle, a plunger in said sleeve having an aperture through which said shoulder may pass when turned in one position, means for preventing the rotation of said plunger relatively to said sleeve, and a cap screwed to the outer end of said sleeve and containing an aperture fitting the non-circular portion of the shank of the tool, whereby turning of the tool and cap relatively to the sleeve brings said shoul- 115 120 125 130

der upon the tool shank and out of alignment with the aperture in said plunger.

4. In combination with a handle containing a reciprocating hammer, a tool having a shank, the outer portion of which is non-circular in cross-section and the inner portion of which is of less diameter than said outer portion, a shoulder upon the inner portion of the shank, a sleeve surrounding the shank of the tool and attached to the handle, a plunger in said sleeve having an aperture through which said shoulder may pass when turned in one position, means for preventing the rotation of said plunger relatively to said sleeve, a cap screwed to the outer end of said sleeve and containing an aperture fitting the non-circular portion of the shank of the tool, whereby rotation of the tool and cap brings said shoulder upon the tool shank into and out of alignment with the aperture in said plunger, and means for locking the cap to the sleeve comprising engaging means upon one of said members and spaced engaging means upon the other 25 of said members so arranged that when first-mentioned engaging means is in engagement with one of said second-mentioned engaging means the shoulder upon the tool shank is in alignment with the aperture in the plunger and when said first-mentioned engaging means is in engagement with the other of said second-mentioned engaging means the shoulder upon the tool shank is out of alignment with said aperture.
5. In combination with a handle containing a reciprocating hammer and having a central aperture for the insertion of the shank of a tool, a sleeve attached to said handle and surrounding said aperture, a plunger in said sleeve containing an elongated aperture, means for preventing said plunger from turning relatively to said sleeve, resilient means tending to urge said plunger toward said handle, a tool having a shank adapted to fit the aperture in said handle, a shoulder projecting from one side of the shank of said tool adapted to pass through the aperture in said plunger when the tool is turned in one direction and to engage said plunger and prevent the withdrawal of the tool when turned in another direction and having a cam surface adapted to engage said plunger and force it outwardly when said tool is turned from the position in which said shoulder registers with said aperture, and releasable engaging means separate from said plunger for preventing said shank from turning relatively to said sleeve.
6. In combination with a handle containing a reciprocating hammer, a sleeve attached to the handle, a plunger in said sleeve containing an elongated aperture, means for preventing said plunger from turning relatively to said sleeve, a cap screwed to the

outer end of said sleeve and containing a non-circular aperture, a tool having a shank, the outer portion of which is non-circular in cross-section and fits the aperture in said cap and the inner portion of which is of less diameter than the outer portion and an eccentric shoulder upon the inner portion of said shank adapted to pass through the aperture in said plunger when the tool is turned in one direction and having a cam surface adapted to engage said plunger and force it outwardly when the tool and cap are turned relatively to the sleeve from the position in which said shoulder registers with said aperture.

7. In combination with a handle containing a reciprocating hammer, a sleeve attached to the handle, a plunger in said sleeve containing an elongated aperture, means for preventing said plunger from turning relatively to said sleeve, a cap screwed to the outer end of said sleeve and containing a non-circular aperture, a tool having a shank, the outer portion of which is non-circular in cross-section and fits the aperture in said cap and the inner portion of which is of less diameter than the outer portion, a shoulder projecting from one side of the inner portion of said shank adapted to pass through the aperture in said plunger when the tool is turned in one direction and having a cam surface adapted to engage said plunger and force it outwardly when the tool and cap are turned relatively to the sleeve from the position in which said shoulder registers with said aperture, and releasable locking means adapted to lock the cap to the sleeve when the shoulder upon the tool shank is out of alignment with said aperture.

8. In a tool-guide for automatically operated tools, the combination of a sleeve, a plunger in said sleeve having an elongated aperture, and means for preventing said plunger from turning relatively to said sleeve, comprising a screw having a threaded connection with said plunger and a square head lying in the groove in said sleeve, the engagement of said head with the walls of said groove preventing said screw from unscrewing.

9. In a tool-guide for automatically operated tools, the combination of a sleeve, a plunger containing an elongated aperture in said sleeve, a cap screwed into the outer end of said sleeve, and a compression spring cooperating with said plunger and said sleeve and held in central position within said sleeve by engagement of one of its ends with a groove in said cap.

10. A tool for use in a device of the class described, comprising a cutting or hammering portion, and a shank, the outer portion of which is non-circular in cross-section and the inner portion of which is of less di-

ameter than the outer portion and is provided with oppositely disposed shoulders, each of said shoulders having an inclined cam surface on one of its outer edges.

- 5 11. The combination of a tool having a shank, the outer portion of which is non-circular in cross-section and the inner portion of which is of less diameter than the outer portion and provided with a shoulder, 45 and a tool retainer provided with a first disc containing an elongated aperture adapted to permit the passage of said shoulder when the tool is turned in one direction relatively thereto and a second disc containing an aperture fitting the non-circular portion of the tool shank, and releasable locking means for restraining rotation of said second disc with respect to said first disc.
- 20 12. In combination with a handle containing a reciprocatory hammer, a tool having a shank, the outer portion of which is non-circular in cross-section and the inner portion of which is of less diameter than the outer portion and is provided with a shoulder, and a tool retainer comprising a sleeve attached to the handle and surrounding the shank of the tool, a plunger in said sleeve having an aperture through which said shoulder may pass when turned in one position relatively thereto, means for preventing the rotation of said plunger relatively to said sleeve, a disc rotatably mounted on said sleeve and containing an aperture fitting the non-circular portion of the shank of the tool whereby rotation of the tool and disc relatively to the sleeve brings said shoulder upon the tool shank into and out of alignment with the aperture in said plunger, and releasable locking means arranged 50
- 25 30 35 40

to lock the disc to the sleeve in a position in which said shoulder is out of alignment with said aperture.

13. In combination with a handle containing a reciprocatory hammer, a sleeve attached to said handle, a plunger in said sleeve, means for preventing said plunger from turning relatively to said sleeve, a tool having a shank adapted to extend into said sleeve, cooperating engaging means 55 upon said plunger and said shank to retain said shank within the sleeve and to permit said shank to be withdrawn when turned in one direction relatively to the sleeve, and releasable engaging means separate from said plunger for preventing said shank from turning relatively to the sleeve.

14. In combination with a handle containing a reciprocatory hammer, a sleeve attached to said handle, a plunger in said 60 sleeve, means for preventing said plunger from turning relatively to said sleeve, resilient means tending to urge said plunger towards said handle, a tool having a shank adapted to extend into said sleeve, 65 cooperating engaging means upon said plunger and said shank to retain said shank within the sleeve and to permit said shank to be withdrawn when turned in one direction relatively to the sleeve, and releasable engaging means separate from said 70 plunger for preventing said shank from turning relatively to the sleeve.

In testimony whereof I have hereunto set my hand in the presence of two subscribing 75 witnesses.

JOHN S. DONALDSON.
